14 Claims. (Cl. 317—200)

The present invention relates to a system for focussing an electron beam within a vacuum envelope, which focussing system comprises a plurality of coaxially arranged annular magnets, there being ferromagnetic pole shoes of different polarity arranged between alternate pairs of successive magnets. Such a focussing system is particularly adapted for use in travelling-wave tubes.

It is known to focus an electron beam, for example in a travelling-wave tube, by means of so-called periodic magnetic focussing systems. Such focussing systems generally consist of several permanent magnet rings or electromagnetic coils which surround the tube and are arranged next to each other, with consecutive magnets having opposing magnetic polarities.

It is also known, in such periodic focussing systems, to provide ferromagnetic annular discs between the individual magnets, that is to say, for example, between the individual magnet rings which are magnetized in axial direction, which ferromagnetic annular discs are fashioned as pole shoes which surround the tube.

One difficulty with the above-described periodic magnetic focussing systems, is that the magnetic characteristics of the individual parts thereof, i.e., the actual magnets and the pole shoes arranged therebetween, will fluctuate beyond acceptable tolerances. Consequently, the amplitude and position of the magnetic focussing field within the tube will fluctuate beyond acceptable limits. The disturbance of the magnetic field is particularly marked if, for example, all or part of a magnet is omitted between two pole shoes, as is sometimes necessary if, for instance, a wave guide for coupling high frequency energy to or decoupling such energy from the tube has to pass through the focussing system.

It is, therefore, an object of the present invention to provide a focussing system which overcomes the above drawbacks, namely, a focussing system by means of which a more homogeneous focussing field is produced. According to the present invention, this is accomplished by interconnecting the pole shoes of like polarity with at least one ferromagnetic yoke. Consequently, the magnetic potential between each two adjacent pole shoes of different polarity will be the same. The balancing effect of the ferromagnetic yokes according to the present invention is sufficiently large so that an appreciable disturbance of the focussing field is avoided even if one or more magnets is omitted so as to allow one or more wave guides to be connected to the travelling-wave tube. Each yoke is, in practice, made of a material of high permeability having a sufficiently high saturation field strength.

Additional objects and advantages of the present invention will become apparent upon consideration of the following description when taken in conjunction with the accompanying drawings in which:

FIGURE 1 is a sectional view of one embodiment of a focussing system according to the present invention.

FIGURE 1a is a perspective view of a pole shoe according to the present invention, there also being shown a web for connecting the actual pole shoe portion with the yoke.

FIGURE 2 is a plan view of another embodiment of a focussing system according to the present invention in

2

which each pole shoe has two webs by which it is connected to yokes.

FIGURE 2a is a perspective view of a section of the structure shown in FIGURE 2.

FIGURE 3 is a sectional view of a focussing system according to the present invention in which a coupling line is provided.

FIGURE 4 is a perspective view showing the interposition of coupling line.

- 10 Referring now to the drawings and to FIGURES 1 and 1a thereof in particular, the same show a focussing system for focussing an electron beam within a vacuum envelope V, the focussing system comprising a number of magnet means constituted by axially magnetized, coaxially arranged and spaced-apart ring magnets 1 of alternating polarity, i.e., each magnet (except the end magnets) has a N-pole directed toward a N-pole of one adjacent magnet and a S-pole directed toward a S-pole of the other adjacent magnet. Pole shoes 2 are arranged between the ring magnets. Each pole shoe has a web 3, the position of the webs 3 being so selected that they join one of two yokes 4 and 5; as shown in FIGURE 1, each of the pole shoes interposed between two N-poles has its web connected to yoke 4 while each of the pole shoes interposed between two S-poles has its web connected to yoke 5.

The pole shoes can be fashioned in any desired manner. In the embodiment illustrated in FIGURES 1 and 1a, each pole shoe has at its inner periphery an enlarged pole shoe portion surface 6 and two laterally extending flanges 7 (FIGURE 1a); in this way, the ring magnets 1 may simply be slipped over the flanges so that the pole shoes serve also as the mechanical mounting means for holding the ring magnets in place. There can be as many webs per pole shoe as desired; in the illustrated embodiment, there is but one web for each pole shoe and the arrangement of the parts in such that the webs of pole shoes of different polarity are diametrically opposite each other.

If desired, one or more ring magnets can be omitted, for example the two end rings, so as to accommodate hollow wave guides by means of which the travelling-wave tube is coupled to another component, such as a source of high-frequency energy.

In the embodiment of FIGURES 2 and 2a, the pole shoes are in the form of rectangular plates 21 provided with an opening 22 through which is inserted the tube that is to be focussed. The pole shoes 21 and 23, shown as being angularly displaced by 90°, represent pole shoes of opposite polarity. Arranged between the pole shoes 21, 23, is an annular magnet 24 constituted, in the instant embodiment, by an electromagnetic coil. The webs of pole shoes 23 (only one of which is illustrated) are connected by two diametrically opposite yokes 25 while the webs of the pole shoes 21 (of which, likewise, only one is shown) are connected by two diametrically opposite yokes 26. In the illustrated embodiment, the yokes 25 and 26, which are preferably plate members of rectangular cross section, also serve as a screening means for the entire magnetic system.

The ferromagnetic yoke means will generally be arranged exteriorly of the outer periphery of the magnets, as shown in the above-described two embodiments. The invention has been found to be particularly advantageous when the magnets are axially magnetized permanent magnets. The pole shoes between the magnets can be of any suitable configuration. The pole shoes are connected with their respective yokes by means of ferromagnetic webs which are at least magnetically connected with the pole shoes.

In the embodiment of FIGURE 3, the focussing system comprises magnets 35 and 38 arranged with alternate

polarity, there being pole shoes 37 interposed between facing N-poles and pole shoes 36 between facing S-poles. The pole shoes of like polarity are interconnected by yokes; only yokes 34 connecting the pole shoes 37 are illustrated, the yokes which connect the pole shoes 36 being similarly constructed as, for example, shown in FIGURE 2.

The embodiment of FIGURE 3 also includes radially magnetized rings 32 arranged at the ends of the focussing system, with only the left-hand ring 32 being illustrated. The outer periphery of the rings engages the yoke or yokes 34; as shown in FIGURE 3, the outer periphery of the radially magnetized ring is a N-pole, as are the yokes 34, so that the outer periphery of ring 32 is in contact with a yoke of like polarity. The inner periphery of the ring 32 is provided with a pole shoe ring 39. The space between the radially magnetized ring 32 and the last pole shoe ring 37, which otherwise would be occupied by another axially magnetized ring magnet, is here shown as being occupied by a hollow conductor 31 by means of which high-frequency energy is coupled to the tube to be focussed. The radially magnetized ring thus takes over, to a certain extent, the function of a pole shoe. The intensity of this ring 32 can, for purposes of controlling the focussing field, be regulated by means of a magnetic shunt 33 which is made, for example, of a ferromagnetic annular disc. The shunt 33 will be suitably supported, e.g., by a plastic ring 33a interposed between the shunt and the yokes 34.

FIGURE 4 shows a hollow conductor 47 arranged next to a pole shoe 41 provided with a web 43. The pole shoe is fashioned as shown in FIGURE 1a, except that it has a flange 7 only on that side which faces away from the hollow conductor 47, thereby to leave space for the conductor. The diametrically opposite yokes 44 and 45 are of different polarity. Of the permanent ring magnets, only magnet 42 is visible.

It will be understood that the above description of the present invention is susceptible to various modifications, changes, and adaptations, and the same are intended to be comprehended within the meaning and range of equivalents of the appended claims.

What is claimed is:

1. For use with a vacuum envelope, a system for focussing an electron beam within the envelope, said focussing system comprising, in combination:
  - (a) a plurality of coaxially aligned and spaced-apart annular magnet means each having axially spaced-apart N and S poles, said magnet means being arranged so that any one magnet means has its N-pole directed toward the N-pole of an adjacent magnet means and its S-pole directed toward the S-pole of an adjacent magnet means;
  - (b) a set of first pole shoes each interposed between two respective facing N-poles;
  - (c) a set of second pole shoes each interposed between two respective facing S-poles;
  - (d) first yoke means magnetically connecting said set of first pole shoes to each other; and

- 4
- (e) second yoke means magnetically connecting said set of second pole shoes to each other.
  2. A focussing system as defined in claim 1 wherein each of said magnet means comprises an electromagnetic coil.
  3. A focussing system as defined in claim 1 wherein each of said magnet means comprises a permanent magnet.
  4. A focussing system as defined in claim 1 wherein said pole shoes encompass the vacuum envelope.
  5. A focussing system as defined in claim 1 wherein said pole shoes comprise a pole shoe portion and at least one web for connecting the respective pole shoe portion with the respective yoke means.
  - 10 6. A focussing system as defined in claim 5 wherein said two yoke means are arranged diametrically opposite each other.
  7. A focussing system as defined in claim 1 wherein each of said yoke means comprises two yokes, and wherein in each of said pole shoes comprises a pole shoe portion and two webs for connecting the respective pole shoe portion with the two yokes of the respective yoke means.
  - 20 8. A focussing system as defined in claim 7 wherein the two yokes of each yoke means are arranged diametrically opposite each other, said first and second yoke means being displaced 90° relative to each other.
  - 25 9. A focussing system as defined in claim 8 wherein each of the four yokes comprise a plate member, said four plate members as a whole serving as a screening means for the entire magnetic system.
  - 30 10. A focussing system as defined in claim 1 wherein said focussing system further comprises two radially magnetized permanent ring magnets arranged coaxially with said set of magnet means; said ring magnets being located adjacent the first and the last of said set of magnet means, respectively; the outer periphery of each of said ring magnets being magnetically connected with the particular yoke which is of the same polarity as the respective outer periphery.
  - 35 11. A focussing system as defined in claim 10 wherein a high-frequency coupling line is arranged between one of said ring magnets and the nearest of said magnet means.
  - 40 12. A focussing system as defined in claim 10 wherein said focussing system further comprises magnetic shunt means arranged adjacent said ring magnets.
  - 45 13. A focussing system as defined in claim 1 wherein said pole shoes comprise means for holding said magnet means.
  - 50 14. A focussing system as defined in claim 13 wherein said holding means comprise annular flanges integral with said pole shoes, said magnet means being permanent magnet rings which encompass said flanges so as to be held thereby.
